UNITED STATES PATENT OFFICE.

EDWARD S. PRESTON, OF CHICAGO, ILLINOIS, ASSIGNEE TO EDMUND & JONES CORPORATION, A CORPORATION OF NEW YORK.

VEHICLE LAMP.

1,427,631.

Specification of Letters Patent. Patented Aug. 29, 1922.

Application filed October 15, 1921. Serial No. 507,652.

To all whom it may concern:

Be it known that I, EDWARD S. PRESTON, citizen of the United States, residing at Chicago, in the county of Cook and State of Illinois, have invented certain new and useful Improvements in a Vehicle Lamp; and I do hereby declare the following to be a full, clear, and exact description of the invention, such as will enable others skilled in the art to which it appertains to make and use the same.

My invention relates to lamps of the general class employed for projecting light in the form of a beam, such as the lamps commonly employed on vehicles, its general objects being those of providing an unusually simple and inexpensive construction and one which will readily lend itself to compactness and neatness of appearance. More particularly, my invention aims to provide a lamp casing, reflector and socket assembly of unusual simplicity and effectiveness and one that will be suitable for use as the tail lamp of an automobile. Furthermore, my invention aims to provide a lamp casing and reflector assembly which will readily afford room for the contact-carrying and lamp-holding parts of an incandescent lamp socket without requiring either projecting formations on the casing or an undue length of the casing. It also aims to provide simple means for holding the reflector within the casing firmly and in properly centered position, and desirably aims to employ these same holding means also for supporting the lamp socket and for housing the major portion of the latter.

More particularly, my invention aims to provide a lamp casing and reflector assembly which will afford ample room for the major portion of the lamp socket between the central portions of the reflector and the back of the casing, and aims to provide reflector-holding means which can readily be employed with socket shells of the bayonet-catch type as commonly used in connection with automobile lamps. It also aims to provide a socket arrangement for this purpose which can readily be wired from outside the casing without requiring clumsy or unsightly projections and one which will require very few parts for its construction. Still further and also more detailed objects will appear

from the following specification and from the accompanying drawings, in which—

55

Fig. 1 is a partially sectioned side elevation of a lamp embodying my invention, showing the same as attached to the rear fender of an automobile.

Fig. 2 is a rear view of the lamp of Fig. 1, drawn on a reduced scale.

Fig. 3 is an enlarged central and longitudinal section of the lamp socket and the adjacent casing and reflector portions, showing the method of connecting the casing of the lamp with the reflector and the socket shell.

Fig. 4 is an elevation of the lamp socket as it appears before being attached to other portions of the lamp.

70

Fig. 5 is a fragmentary section of the socket and reflector holding tube showing the shape of its end before the parts are assembled.

In one of its immediate commercial applications, my invention is particularly suitable for the construction of so-called tail lamps or stop signal lamps as designed for attachment to the rear fenders of automobiles, and I am therefore illustrating and describing the same in such an embodiment, although I do not wish to be limited to this use of my invention. In the illustrated type, the lamp of my invention includes a casing 1 having a substantially cylindrical forward portion equipped at its forward end with a diametrically enlarged flange 2 for receiving a lamp front or lens 3, which lamp front is held in position by a clamp 4 surrounding the flange 2 and tightened by a bolt 5. The casing 1 desirably has its rear portion substantially in the shape of a dome so as to form a forwardly concaved back, thus making a casing which can easily be manufactured by a single drawing operation and which will have those curved lines which add to the appearance of the lamp and which make it seem less bulky in proportion to its size.

Disposed within this casing is a reflector 6 which is also concaved forwardly of the lamp but on a considerably larger radius of curvature than the back of the casing. This reflector, which forms an auxiliary back portion for the casing, has a diameter approaching, but preferably somewhat smaller

than, the bore of the cylindrical portion of the casing. This reflector is inserted within the casing coaxial with the latter and is firmly held in such a position that the edge 5 of the reflector bears rearwardly of the lamp against some portion of the casing, such as the curved back portion somewhat rearwardly of the cylindrical part of the casing. To hold the reflector firmly in this position I 10 provide the back of the casing and the reflector with aligned openings coaxial of both of these parts and connect these two parts by a cylindrical anchoring tube 7 which extends slightly through the said aligned 15 perforations in both the reflector and the back of the casing and which has each extreme end interlocked with the perforated lamp part through which it projects. For this purpose, I desirably employ a metal tube of 20 slightly larger diameter than the bore of the perforations of the reflector and the casing, each end of the tube being suitably reduced in outside diameter for short distance after the manner of Fig. 5 so that this smaller end 25 portion can be inserted through one of the said perforations. After assembling the said three parts with the tube 7 in axial alignment with the lamp casing and reflector and with its ends projecting through both of the 30 said perforations, I spin the projecting forward end of the tube 7 over the front of the reflector and likewise spin the rear end of the tube over the outside of the back of the casing. As this is done with the reflector 35 contacting at its periphery with the concave portion of the casing, the interlocking of the tube with the casing and reflector anchors the reflector firmly within the casing so that it cannot shift in position in any 40 direction. Indeed, the original length of the tube is desirably so proportioned that the spinning operation will slightly flex the reflector to decrease the radius thereof, thereby by spring it into firm peripheral engagement 45 with the casing.

Having thus provided a firm and inexpensive mounting for the reflector within the casing, I desirably employ the spacer tube or anchoring tube 7 also as the housing for 50 the current-carrying electric terminal and for the base of the incandescent lamp which is to furnish the illumination. For this purpose, I preferably make the tube 7 of such a bore that it will slidably fit over the exterior 55 of a cylindrical socket shell 8 of the size commonly employed in automobile lamp sockets, thereby permitting the socket proper to be assembled in advance and then affixed to the lamp. As here shown, the socket construction 60 includes a cylindrical shell 8 slightly longer than the anchoring tube 7 and slidably fitting into the bore of the latter and equipped at its forward end with the usual opposed bayonet catch slots 9 for interlocking 65 with the lateral projections on the base of a lamp. Into the rear of this shell 8 I insert the cylindrical portion 10 of an insulator which has a head 11 of larger diameter than the anchoring tube 7, and I desirably anchor this insulator within the shell 8 by 70 slightly indenting the shell at several points after the manner shown at 12 in Fig. 3 and in Fig. 4. The insulator comprising the cylindrical plug 10 and the head 11 has an axial bore extending through the same and 75 this bore houses the major portion of a wire terminal 24 which has its forward portion formed into a cylinder for holding both the enlarged head of a forwardly projecting plunger 13 and a spring 14 continually pressing the said head forward after the manner 80 customary in lamp socket constructions. The terminal 24 is suitably anchored within the insulator, as for example by equipping it with a pair of fingers 15 which are imbedded in the insulator when the wire terminal is driven into the latter, the insulator having previously been suitably softened by steaming so as to permit the fingers to force 85 their entry. The wire terminal 24 also has a transverse bore aligning with a corresponding bore in the head 11 of the insulator so that the tip of a wire 16 can be inserted into the said transverse bore in the wire terminal and clamped in position by a binding screw 90 17. The wire 16 then furnishes a circuit connection from one terminal of the lighting circuit to the plunger 13, the other terminal of the circuit being grounded through the metal frame of the vehicle to the shell of 95 the casing and hence to the socket shell 8, after the manner customary in grounded wire automobile lighting practice.

After the socket has thus been assembled, I insert its metal shell from the rear of the 100 casing through the bore of the tube 7 and spin the projecting forward end of the tube 8 over the adjacent forward end of the tube 7. By doing so, I can readily lock the entire socket assembly in effective position 110 without requiring any auxiliary fastening elements, as the engagement of the rear end of the anchoring tube 7 with the shoulder 20 (or annular forward portion of the head 11) prevents a forward movement of the 115 socket within this tube, while the outwardly flared forward end of the socket shell 8 prevents rearward movement and also clamps the socket against rotation within the anchoring tube.

From the above it will be obvious that the entire lamp construction is exceedingly simple, compact and inexpensive. It will also be evident that the major portion of the lamp 120 socket is entirely concealed in the space between the reflector and the rear end of the casing, so that no unsightly projection is required at the back of the casing for affording the needed room. The only projecting part is the head 11 of the insulator which 125

can be relatively short and which desirably is knurled as shown in Fig. 4 so as to afford a handsome finish for the rear of the lamp. Where the lamp is to be attached to a fender, 5 I desirably rivet a pair of brackets 18 to the lamp casing and pivot these on a bolt 19 between a corresponding pair of brackets 22 which are curved for attachment to the fender. However, I do not wish to be limited to 10 any particular method of supporting the lamp casing, nor to the particular shape of parts or to other details of the construction and arrangement above disclosed, it being obvious that the same might be modified in many 15 ways without departing from the spirit of my invention or from the scope of the appended claims.

I claim as my invention:

1. A lamp comprising a casing and a reflector housed thereby, the reflector and the rear of the casing having alined apertures, an anchoring tube extending through the said alined apertures and equipped at each end with a groove, the said groove being respectively entered by the aperture walls of the reflector and the casing, and a lamp socket having its shell housed by and clamped to the said tube.

2. In a lamp, a casing having a dome-shaped rear end, a reflector disposed within the casing and having its edge engaging the interior of the said dome-shaped end, the reflector and the said end having axial apertures, an anchoring tube coaxial with the 35 said apertures and interlocked at its ends respectively with the said end and reflector, and a complete lamp socket having its shell housed by the anchoring tube and flared over the forward end of the latter and having another portion engaging the rear end of the anchoring tube.

3. In a lamp, a casing having a forwardly concaved back, a reflector housed by the casing and less concave than the said back and

having its peripheral portion rearwardly 45 bearing against the interior of the casing, the said reflector and back having alined axial apertures, a lamp socket disposed axial of the reflector and casing and extending through the said apertures and a mounting 50 for the lamp socket including a tube housing the shell of the socket and extending through the said apertures and having its ends respectively spun over the forward face of the reflector and the rear of the said back. 55

4. In combination, a lamp casing, a reflector disposed therein and having its central portion spaced from the back of the casing, the said back and reflector having an anchoring tube extending through the said perforations and interlocked at its ends respectively with the said back and reflector to rigidly space the same, and a lamp-socket having its shell housed by the said tube and flared at its forward end over the forward 65 end of the said tube, the socket including an insulating body anchored to the socket shell and having an annular shoulder engaging the rear end of the said tube.

5. In combination, a lamp casing, a reflector disposed therein and having its central portion spaced from the back of the casing, the said back and reflector having alined perforations, an anchoring tube extending through the said perforations and secured 75 to both said back and reflector, and a lamp-socket extending through the said tube and including a shell and an insulator fastened thereto, the socket shell being formed for engaging the said tube to prevent rearward 80 movement within the latter and the insulator being formed for engaging the rear end of the tube to prevent forward movement of the socket.

Signed at Chicago, Illinois, October 13th, 85
1921.

EDWARD S. PRESTON.
